[57] **CLAIM**

The ornamental design for a weightlifting plate, as shown and described.

DESCRIPTION

FIG. 1 is a perspective view of one embodiment of a weightlifting plate showing our new design;

FIG. 2 is a front elevational view of the weight lifting plate of FIG. 1, wherein the rear view is identical to the front view;

FIG. 3 is a perspective view of an alternate embodiment of a weightlifting plate showing our new design; and,

FIG. 4 is a front elevational view of the weight lifting plate of FIG. 3, wherein the rear view is identical to the front view. The broken line portions of the drawing disclosure are for illustrative purposes only and form no part of the claimed design.
